UNITED STATES PATENT OFFICE.

EDWARD P. ROTHACKER, OF CLEVELAND, OHIO.

SLIP JACKET AND METHOD OF MAKING IT.

Application filed January 14, 1920. Serial No. 351,447.

To all whom it may concern:

Be it known that I, EDWARD P. ROTHACKER, a citizen of the United States, residing at 2560 E. 84th St., in the city of Cleveland, 5 county of Cuyahoga, and State of Ohio, have invented a new and useful Improvement in Slip Jackets and Methods of Making Them, of which the following is a specification, the principle of the invention being herein explained, and the best mode in which I have contemplated applying that principle so as to distinguish it from other inventions.

My invention relates both to a slip jacket 15 for foundry use and to the method of casting the same.

Slip jackets are used to replace a flask to confine a finished mold until and during the time when metal is to be poured into the 20 mold. Slip jackets being less expensive than flasks are employed to enable prompt reuse of the flask in the preparation of duplicate molds. Slip jackets may have either straight or sloping sides and have heretofore, been of composite construction usually comprising steel plates welded or otherwise secured together at the corners. Experience has demonstrated however, that slip 25 jackets so constructed become warped.

I propose the manufacture of slip jackets cast in one piece, mindful of the fact that cast iron holds its shape regardless of alternate heating and cooling. It is essential that the walls of a slip jacket be smooth 30 and precisely formed in order that equisized jackets may be interchangeable and to insure against the sand bulging out over even relatively small areas during the pouring operation. Besides the factor of economy, it is manifest that minimum weight is 35 an advantage, and I have discovered that the thickness of cast iron slip jackets need not exceed three-sixteenths of an inch.

I have provided the sides of my slip 40 jacket with means whereby wooden handles 45 may be detachably connected, wood being of good insulation against heat and due to its cheapness may be frequently replaced, This feature of my invention I believe to be 50 patentably novel.

Known foundry practice does not enable the successful production of cast slip jackets because of the impossibility of withdrawing the pattern if the sand is packed on both 55 sides of the latter in the same mold, and because a cast slip jacket cannot reliably be

made with a core which would become distorted in shape. Except for the handle lugs, in preparing the mold according to my invention, I employ only green sand. Another seeming obstacle which I have overcome is to make possible the insertion of a gate pattern because, as those skilled in the art will readily discern, a uniform feeding and spread of metal to the mold cavity 60 is desirable if not indeed necessary.

This application is to be considered, in respect to all common subject matter, a continuation of my earlier application filed 65 May 12, 1919, Serial No. 296,697.

Advertising to the drawings:—

Figure I is a top plan view of cast metal 70 slip jacket embodying my invention, a suggested shape of gate being indicated in dotted lines.

Figure II is a side elevation of the same.

Figure III is a sectional view showing the jacket in place around a mold.

Figure IV is a bottom plan view of my 75 design for slip jacket, likewise showing in dotted lines a suggested form of gate.

Figure V is a plan view of the pattern of the drag with the pattern of the lower gate in place.

Figure VI is a section on line VI—VI of 80 Figure V with the flask for the drag side surmounted thereon.

Figure VII is a similar view showing the drag turned over and the drag pattern removed from its mold and also showing a 85 simple sprue.

Figure VIII is a plan view of the cope pattern with the pattern of the upper gate in place.

Figure IX is a section through a core for 90 making a handle retaining lugs on the jacket.

Figure X is a section on line X—X of 95 Figure VIII with the flask for the cope side inverted upon a follow board.

Figure XI is a median section of the completed mold.

The illustrated slip jacket consists of a four sided frame 1 provided on each of oppositely disposed sides with a pair of lugs 2 forming a dove-tailed channel for the insertion of wooden handles 3. It should be understood that the handles 3 are removable fitted in place so that whenever they become over charred or burned they may be removed and replaced with new ones. In Figure III the slip jacket is shown em-

bracing a mold 4 including a cavity 5 to which a sprue 6 leads.

The method of casting a slip jacket of thin light construction and of uniform thickness proved to be a problem the solution of which I will now describe.

A hollow box or female pattern 7 is provided with a cavity 8 which is open above as shown in Figure VI. The pattern 7 carries on opposite sides angle irons 9 provided with holes 10. After filling the cavity 8 with sand and suitably packing the same level with the upper surface 11 of the pattern, I lay thereon a gate pattern having the shape shown in Figures IV and V. It will be understood that the shape of the gate pattern 12 may be varied provided it enables the metal to spread uniformly toward the sides. A flask 13 stiffened by cross bars 14 carries on opposite sides angle irons 15 provided with pins 16. As is common practice, the pins 16 are adapted for insertion in the holes 10 to hold the flask in its proper surmounted position. Next the flask 13 is filled and rammed up with sand 17 thereby, of course enclosing the gate pattern 12. The flask 13 for the drag side is then lifted to enable the gate pattern 12 to be drawn and removed. Then a sprue 18 is cut. Thereupon the flask 13 is again placed over the pattern 7 and both members inverted in the usual manner upon a floor. Next the form pattern 7 is lifted away from the sand form 19 which occupied the cavity 8, as appears in Figure VII.

Another flask 20 provided with lateral irons 21 having holes 22 is similarly stiffened by bars 23. The flask 20 is to be mounted upon a follow board 24 provided with angle irons 25 which carry pins 26. A block or male pattern 27 is fastened to the upper side of the follow board 24 by means of screws 28. Two oppositely disposed sides of the pattern 27 are fashioned each with a pair of inclined core prints 29 to eventually produce cavities for the reception of four cores 30 provided with interiorly open cut-outs 31 separated by a core section 32. Such core is shown in Figure IX and is shaped to enable the formation of the two lugs 2 as will be readily understood by those skilled in the art. Carried upon the top of the pattern 27 integrally or detachably is a gate pattern 33 of the same shape as the gate pattern 12. After the flask 20 is fitted upon the follow board 24 so as to enclose patterns 27 and 33 as appears in Figure X, it is filled with sand and suitably packed. Then a central sprue 34 is cut down to the pattern 33, after which the flask 20 and follow board 24 are together inverted upon another board or floor not shown. Following this, the screws 28 are removed, the follow board 24 removed and the patterns 27 and 33 drawn after having been previously rapped. It is

at this stage, that the four cores 30 are placed in the core print cavities left after the withdrawal of the core prints 29. The flask 20 for the cope side is now again inverted and placed over the flask 13 for the drag side, the pins 16 of the latter passing through the holes 22 of the former, in which position the sprue 34 is directly over or in registry with the sprue 18 and the mold completed as appears in Figure XI. The mold will be seen to include a cavity 35 for the upper gate, a cavity 36 for the lower gate and a cavity 37 for the slip jacket casting.

I claim:

1. The method of casting a slip jacket which consists in making a male sand mold section, fashioning the top of a larger female sand mold with gate sprue, and cutting a sprue through said female sand mold to cause it to communicate with said gate sprue, and introducing molten metal to said sprues.

2. The method of casting a slip jacket which consists in making a female sand mold section, fashioning the bottom of a smaller male sand mold with gate sprue, and cutting sprues through both male and female sand molds to cause them to communicate with said gate sprue, and introducing molten metal to said sprues.

3. The method of making a slip jacket which consists in filling a box pattern with sand, enclosing with sand a block pattern larger than the interior of said box pattern, removing said patterns, bringing said mold portions into juxtaposition, and causing molten metal to flow both upwardly and downwardly around said mold.

4. The method of making a slip jacket which consists in superimposing a flask upon a box pattern, filling both pattern and flask with sand placing a block pattern larger than the interior of said box pattern upon a follow board, enclosing said block pattern by laying a flask upon said follow board, filling said flask with sand, inverting both flasks and molds leading sprues to each mold cavity withdrawing said patterns, replacing the block mold cavity over the box mold cavity to effect a registry of said sprues and causing molten metal simultaneously to flow through said sprues.

5. The method of making a slip jacket which consists in superimposing a flask upon a box pattern, filling both pattern and flask with sand, cutting a sprue, enclosing with sand a block pattern larger than the interior of said box pattern, cutting a sprue, removing said patterns, bringing said mold portions into juxtaposition so that said sprues register, and causing molten metal to flow around said mold upwardly from the bottom of one sprue and downwardly from the bottom of the other sprue.

6. The method of casting a slip jacket which consists in straddling the upper open

side of a box pattern with a gate pattern, covering with a flask for the drag side, packing said box pattern, the interstices of said gate pattern and said drag flask with sand, inverting the parts, lifting the box pattern laying a flask for the cope side upon a follow board which carries a block pattern so that said flask encloses said patterns filling said cope flask with sand, inverting, drawing the patterns and covering the drag supported mold with the cope supported cavity.

7. The method of casting a slip jacket which consists in laying a gate pattern across the top of an open box pattern, covering with a flask for the drag side, packing opposite sides of said gate pattern with sand, inverting the parts, cutting a sprue, lifting the box pattern, laying a flask for the cope side upon a follow board which detachably carries a block pattern and surmounted gate pattern so that said flask encloses said patterns filling said cope flask with sand, inverting, cutting a sprue, drawing the patterns, covering the drag supported mold with the cope supported cavity, and pouring molten metal simultaneously through said sprues.

8. The method of casting a slip jacket which consists in filling a female pattern with sand laying a gate pattern thereon, covering with a flask for the drag side, packing said drag flask with sand, cutting a central sprue to said gate pattern, lifting the drag flask, removing the gate pattern, replacing the drag flask upon the female pattern, inverting, lifting off the female pattern, laying a flask for the cope side upon a follow board which detachably carries a male pattern and surmounted gate pattern filling said cope flask with sand, inverting, cutting a central sprue to said gate pattern, drawing the female patterns, covering the drag supported mold with the cope supported cavity to bring said sprues into registry, and pouring molten metal simultaneously through said sprues and to all sides of said mold cavity along said gate cavities respectively.

9. A slip jacket provided on opposite sides with laterally extending slots, and handles detachably insertible into said slots.

10. The method of molding which consists in fashioning a main mold cavity with a core print cavity and inserting into said core print a core having cut-outs so that the latter communicate with said main mold cavity, said cut-outs enclosing a dovetail shaped core section.

11. The herein described method of molding which consists in making a looped or endless mold cavity and a core cavity communicating therewith, inserting in said core cavity a hollowed core opening into the looped cavity and causing molten metal simultaneously to flow around said looped

cavity in both directions to fill the core hollows.

12. The method of making a slip jacket which consists in bringing male and female sand portions into juxtaposition, and causing molten metal to flow both upwardly and downwardly around said mold.

13. The method of making a slip jacket which consists in superimposing a flask over a box pattern and a surmounted gate pattern, filling with sand, cutting a central sprue, enclosing with sand a gate pattern and a block pattern larger than the interior of said box pattern, cutting a central sprue, removing said patterns, bringing said mold portions into juxtaposition so that said sprues register, and introducing molten metal to cause it to flow through both central sprues and through said gate sprues and around said mold upwardly from the bottom of one sprue and downwardly from the bottom of the other sprue.

14. The method of casting a slip jacket which consists in straddling the upper open side of a box pattern with a gate pattern, covering with a flask for the drag side, packing said box pattern, the interstices of said gate pattern and said drag flask with sand, inverting the parts, cutting a sprue, withdrawing the patterns to expose the male sand mold; laying a flask for the cope side upon a follow board which carries a block pattern and surmounted gate pattern so that said flask encloses said patterns, filling said cope flask with sand, cutting a sprue, inverting, drawing the patterns, covering the drag supported mold with the cope supported cavity and introducing molten metal to all of said sprues.

15. The method of casting a slip jacket which consists in laying a gate pattern across the top of an open box pattern, covering with a flask for the drag side, packing opposite sides of said gate pattern with sand, separating said box pattern and flask, removing said gate pattern, restoring said box pattern and gate pattern to juxtaposition, inverting the parts, cutting a sprue through the male sand mold, lifting the box pattern from the latter, surmounting a larger female mold over said male mold, cutting a sprue through said female mold so that it will register with said first mentioned sprue and introducing molten metal through said sprues to reach and be distributed through said gates.

16. A cast metal slip jacket provided with wooden handles having a mortise and tenon connection with said jacket, said connections extending horizontally along opposite sides of said jacket.

17. The method of making a slip jacket which consists in bringing male and female sand portions into juxtaposition with the former intersecting the latter so that a pas-

sage for molten metal is provided entirely around said male sand portion, and causing molten metal to flow both upwardly and downwardly around said mold.

5 18. The method of making a slip jacket which consists in bringing male and female sand portions into juxtaposition with the former intersecting the latter so that a passage for molten metal is provided entirely 10 around said male sand portion, providing

communicating sprues in both sand portions and causing molten metal to flow from one sprue across the top and down around said male sand portion and from the other sprue across the bottom and up around said male sand portion. 15

Signed by me, this 13th day of January, 1920.

EDWARD P. ROTHACKER.
